UNITED STATES PATENT OFFICE.

ADOLPH DE CLAIRMONT, OF LOS ANGELES, CALIFORNIA.

APPARATUS FOR GENERATING RADIUM WATER.

Application filed November 17, 1925. Serial No. 69,719.

This invention relates to an apparatus for generating and dispensing radium water. The health giving properties of radium taken internally absorbed in water, are well known, but, so far as I am aware, no satisfactory apparatus has heretofore been devised by which radium water could be produced. Therefore, it is the primary object of the present invention to provide an apparatus by the use of which water may be caused to readily and rapidly absorb radium emanations from material carrying the same, and the water consumed while impregnated with the emanations. 15 Another object of the invention is to provide a simple, inexpensive and compact apparatus for the purpose of generating radium water, which apparatus may be readily supported upon a table and will occupy but little space and may be manually operated, with little exertion, to cause the water introduced thereto to absorb the radium emanations from an element of the apparatus which carries radium emanation material. 20

25 In the accompanying drawings:

Figure 1 is a view in side elevation of the apparatus embodying the invention.

30 Figure 2 is a vertical transverse sectional view taken substantially on the line 2—2 of Figure 1, looking in the direction indicated by the arrows.

The apparatus is mounted upon a suitable base indicated by the numeral 1, and includes a generator 2 which may be made of any material found suitable for the purpose, such for example as metal or porcelain, terra cotta, aluminum, etc. The generator is divided interiorly into upper and lower compartments 3 and 4 respectively, by a circular filtering disc or slab 5 which is preferably of tripoli, the said filtering medium being peripherally supported upon a shoulder 6 within the generator 2 or otherwise held in place. In any event, the medium 5 is intended to close the lower chamber 4.

50 The invention contemplates creating a partial vacuum within the generator chamber 4 at one period in the operation of the apparatus, and introducing air under pressure into said chamber at another period in the operation of the apparatus, and for this purpose a suction pump, indicated in general by the numeral 7, and a pressure pump, indicated in general by the numeral 8, are mounted upon the base 1 at opposite sides of

the generator. These pumps may be of any of the well known types and the pump 7 comprises a cylinder 9 mounted in upright position upon the base 1 and having an exhaust port 10 near its lower end controlled by a check valve 11. A piston 12 is mounted for reciprocation within the cylinder and comprises a rod 13 and head 14, the latter fitting within the cylinder in an air-tight manner and the former extending upwardly through the head 15 of the cylinder and being provided with a handle 16 whereby reciprocatory motion may be readily imparted, manually, to the said piston. The piston is provided with a check valve 17 upon its under side controlling the passage of air through a port 18 formed in the said head. A tube 19 leads from one side of the cylinder, at the upper end thereof and through the wall of the generator, downwardly through the upper chamber 3 thereof with its lower open end extending through the filtering medium 5, a manually operable cut off valve 20 being interposed in said tube between the cylinder 9 and the generator 2. At this point it will be evident that by reciprocating the piston of the suction pump 7, air will be exhausted from the generating chamber 4, and water which is introduced into the reservoir or water chamber 3, will be caused to filter through the filtering medium 5. In this manner, filtering of the water to be impregnated by the radium emanations, is quickly accomplished and transferred to the generating chamber 4.

90 The pump 8 comprises a cylinder 21 having a piston 22 working therein and including a head 23 and stem 24, the latter being provided at its upper end with a handle 25 whereby the piston may be conveniently reciprocated within the cylinder. A pipe 26 is connected at its lower end through the side of the cylinder 21, at the lower end of the cylinder, and a check valve 27 controls the communication between the said pipe 100 and the cylinder, the valve being arranged to provide for delivery of air under pressure through the pipe 26 and into the chamber 4 by way of a downwardly extending branch 28 of said pipe which opens through the filtering medium 5, a manually operable cut off valve 29 being interposed in the pipe 26 between its upper end and the upper end of the branch 28. At this point, it will be evident that air under pressure may be 110

forced into the generating chamber 4 by manually reciprocating the piston 22 of the pump 8.

The chamber 3 is closed at its top by a removable lid or cover 30. A pipe 31 leads from a faucet 32 which is secured in an opening in the wall of the water chamber 3 near the top thereof, and the said pipe extends downwardly within this chamber and through the filtering medium 5 and has its lower end presented close to the bottom of the generating chamber 4 and at this point it will be evident that when there is air under pressure within the generating chamber 4 above the water level therein and the faucet 32 is opened, water will be delivered from the apparatus.

The numeral 33 indicates in general the radium emanation-bearing medium which is employed in the apparatus and, in the embodiment of the invention illustrated in Figure 2 of the drawings, the said medium comprises a hollow open-ended cylinder 34 which is composed or formed of carnotite ore mixed with a suitable binder of clay and molded and baked. This cylinder is disposed in upright position substantially centrally upon the bottom of the generating chamber 4 and is formed with a number of perforations indicated by the numeral 35.

In the operation of the apparatus, the suction pump 7 is operated to effect the filtering of water which has been introduced into the water chamber or reservoir 3, into the generating chamber 4, where it comes in contact with the cylinder 34, the cylinder being, of course, completely surrounded by the water as there is free circulation through the openings 35 in the wall of the cylinder. The quantity of water introduced is such that the water level will be a short distance below the filtering medium 5, and, if found necessary, the suction pump may be again operated at this time so as to create a partial vacuum above the water level. It is a well known fact that water will not retain radium emanations for any considerable period of time and, in the use of the apparatus, the emanations will form a coating upon the wall of the generating chamber 4. Due to the partial vacuum in the space above the water level in the generating chamber, this space becomes charged with radium gas or emanations. When it is desired to obtain the radium impregnated water from the apparatus, the valve 20 being closed, the valve 29 is opened and the pressure pump is actuated until the partial vacuum within the generating chamber 4 has been destroyed and a pressure has been built up in said chamber greater than atmospheric pressure. Then, when the faucet 32 is opened, the outflow of water from the generating chamber results in a

disturbance of the radium emanations in the space above the water therein, thus effecting 65 impregnation of the water with the said emanations and, at the same time, effecting aeration of the water.

Having thus described the invention, what I claim is:

1. In apparatus for generating radium water, a generator comprising a hollow body, a filtering medium dividing the body interiorly into upper and lower chambers, the upper chamber constituting a reservoir for water 75 to be impregnated with radium emanations, a radium emanation-bearing medium in the lower chamber, means for creating a partial vacuum in the lower chamber whereby to effect rapid filtering of the water from the upper to the lower chamber for intimate contact with the said radium emanation-bearing medium, a valved outlet from the lower chamber, and means for destroying said partial vacuum within the lower chamber whereby to provide for discharge of the impregnated water from the said chamber.

2. In apparatus for generating radium water, a generating chamber, a radium emanation-bearing medium in said chamber, a water reservoir located above the chamber, a filtering medium interposed between the said reservoir and the said chamber whereby to filter water delivered from the reservoir to the chamber, means for creating a partial vacuum in said chamber, and means for destroying said partial vacuum whereby to provide for discharge of the impregnated water from the chamber.

3. Apparatus for generating radium water comprising a closed hollow body, a filtering partition dividing the body into an upper storage compartment for water and a lower generator compartment, a radio-active member in the generator compartment, a dispensing pipe leading through a side of the body near the top thereof and extending through the compartments and the filtering partition and terminating adjacent the bottom of the generator compartment, a faucet 110 at the delivery end of the dispensing pipe, other pipes extending through the sides of the body near the top thereof and passing through the storage compartment and the filtering partition and terminating about in the plane of the lower side of the said partition, suction and pressure pumps connected to the last mentioned pipes respectively whereby a partial vacuum and pressure may be successively, independently established in 120 the generating compartment and a controlling valve in the length of each of the pipes between the body and pump.

In testimony whereof I affix my signature.

ADOLPH DE CLAIRMONT. [L. S.]
